CLAIM

The ornamental design for a thin layer chromatography device as shown and described.

DESCRIPTION

FIG. 1 is a front, right, top perspective view of a thin layer chromatography device showing the new design.

FIG. 2 is a front, right perspective view thereof.

FIG. 3 is a front elevation view thereof.

FIG. 4 is a rear elevation view thereof.

FIG. 5 is a left side elevation view thereof.

FIG. 6 is a rear, right, top perspective view thereof; and,

FIG. 7 is a right side elevation view thereof.

The bottom surface of the thin layer chromatography device is flat and devoid of ornamental features.
